UNITED STATES PATENT OFFICE.

MAX STERN, OF BROOKLYN, NEW YORK, ASSIGNOR TO BILTMORE LIGHTING FIXTURE CO., INC., OF BROOKLYN, NEW YORK, A CORPORATION OF NEW YORK.

DESIGN FOR A LIGHTING-FIXTURE BRACKET.

Application filed June 24, 1925. Serial No. 13,882. Term of patent 3½ years.

To all whom it may concern:

Be it known that I, MAX STERN, a citizen of the United States, and a resident of the borough of Brooklyn, Kings County, city and State of New York, have invented a new, original, and ornamental Design for a Lighting-Fixture Bracket, of which the following is a specification, reference being had to the accompanying drawing, forming a part thereof.

Fig. 1 is a front elevation; and

Fig. 2 is a side elevation of a lighting fixture showing my new design.

I claim:

The ornamental design for a lighting-fixture bracket, as shown.

MAX STERN.
